UNITED STATES PATENT OFFICE

167,840

COMBINED CONTAINER AND CANDY CANE
DISPLAY

Robert E. McCormack, Sr., Albany, Ga.

Application August 7, 1951, Serial No. 16,185

Term of patent 14 years

(Cl. D80—5)

To all whom it may concern:

Be it known that I, Robert E. McCormack, Sr., a citizen of the United States, residing at Albany, in the county of Dougherty and State of Georgia, have invented a new, original, and ornamental Design for a Combined Container and Candy Cane Display, of which the following is a specification, reference being had to the accompanying drawing, forming part thereof.

Figure 1 is a plan view of a combined container and candy cane display, showing my new design.

Figure 2 is an end view of the display package, partly in section, showing one of the slotted strip supports which hold the candy canes in place.

I claim:

The ornamental design for a combined container and candy cane display, as shown.

ROBERT E. McCORMACK, Sr.
